UNITED STATES PATENT OFFICE.

HAYMAN SHLAMOWITZ, OF BROOKLYN, NEW YORK.

DESIGN FOR A HEAD-RING FOR ELECTRIC-LIGHT FIXTURES.

55,400.

Specification for Design.

Patented June 1, 1920.

Application filed February 24, 1920. Serial No. 360,997. Term of patent 7 years.

To all whom it may concern:

Be it known that I, HAYMAN SHLAMOWITZ, a citizen of Poland, residing in the city of New York, borough of Brooklyn, in the county of Kings and State of New York, have invented a new, original, and ornamental Design for a Head-Ring for Electric-Light Fixtures, of which the following is a specification, reference being had to the accompanying drawing, forming part thereof.

The figure is a perspective view of a head ring for an electric light fixture and showing my new design.

I claim:

The ornamental design for a head ring for electric light fixtures as shown.

HAYMAN SHLAMOWITZ.
